RADIO-RECEIVING APPARATUS

Carel Jan van Loon, Eindhoven, Netherlands, assignor, by mesne assignments, to Radio Corporation of America, New York, N. Y., a corporation of Delaware

Application February 7, 1939, Serial No. 255,005
In the Netherlands February 8, 1938

8 Claims. (Cl. 172—239)

The invention relates to a radio-receiving apparatus which is adapted to be automatically tuned to a plurality of pre-determined stations with the aid of a station selector consisting of a key-board, a selector disc or a similar device, and wherein the tuning members are actuated by means of a motor.

Such receiving apparatus are known per se. Thus, for example, it has been proposed to mount on the shaft by which the tuning means are actuated a switch arm which brushes along a fixed contact track of which each contact corresponds to a determined station. Upon putting the station selector into operation a voltage is applied to one of the contacts and at the same time the motor which actuates the tuning means is switched into circuit. When tuning to the desired station is attained the switch-arm passes over the contact being under tension and a circuit is closed, which results in the motor being switched out of circuit.

The tuning obtained with such a device is in general not very exact since between the moment when the motor is switched-off and the moment when the tuning means come at rest, there always elapses a certain interval of time during which the tuning means leave the desired position.

Fundamentally it would be possible to obtain greater accuracy by actuating the tuning means at a very slight speed owing to which the removal from the desired position during the above-mentioned lapse of time would be reduced to a small value. Such a device would, however, have the drawback that tuning to a desired station would take too long.

The present invention has for one of its objects the provision of a radio-receiving apparatus with completely automatic tuning which is adapted to be tuned very rapidly to a desired station and wherein nevertheless sufficient accuracy is obtained.

According to the invention, after the station selector has been put into operation the tuning members are initially actuated for this purpose at a high speed which is considerably reduced just before the attainment of correct tuning.

The invention will be explained more fully with reference to the accompanying drawing which represents, by way of example, some embodiments thereof, and wherein Fig. 1 illustrates a modification of the invention utilizing a change speed device; Fig. 1a is a detail of a portion of the structure shown in Fig. 1; Fig. 2 is a detail of a preferred form of variable

transmission means; Figs 3 and 3a are views taken along the line 3—3 of Fig. 1 and show the coupling means in different stages of operation between certain members in the transmission chain; Fig. 4 is another modification of the invention using a reversible motor and a reversing switch device; and Fig. 5 illustrates diagrammatically the change speed mechanism utilized in the modification of Fig. 4 and its manner of operation.

Fig. 1 represents those parts of a radio-receiving apparatus having completely automatic tuning which are necessary for the proper understanding of the invention.

Tuning is effected with the aid of a key-board having a plurality of keys or press-buttons T₁, T₂, T₃ etc. When one of these keys is pressed-in a switch is closed with the result that one contact of the fixed contact track I is connected to a conductor 2. As shown more clearly in Fig. 1a, the contact track I preferably consists of a circular disc of insulating material in which along the circumference a plurality of holes are bored. Through each of these holes passes a conductor 3 which is connected to the fixed contact of one of the switches actuated by the keys. On that side of the circular disc which is remote from the key-board the conductors 3 terminate at a plurality of contacts along which pass contacts I and II of a pair of switch arms which are mounted on the shaft by which the tuning means of the receiver are actuated. The key-board is constructed in such manner that always only a single key can be pressed-in. If another key is pressed-in the key which has initially been pressed-in automatically snaps upwards.

The contacts I and II of the switch arms are connected to secondary windings 4 and 5 respectively of a transformer 6 whose primary winding is connected to the terminals 7 and 8 of the alternating current mains. The ends of the windings 4 and 5 which are remote from the said contacts are connected to the conductor 2 through a conductor 9 and a coupling magnet M whose operation will hereinafter be described in detail. The actuation of the tuning means is effected by means of a motor M_t which may be connected to the alternating current mains via one of the contacts m, h or k. For convenience, these contacts are duplicated elsewhere in Fig. 1 in association with the means which control the contacts. Thus, contacts m are under the control of magnet M, contacts h are under the control of lever 34 and contacts k are under control

of discs 19 and 22, all to be described more fully hereinafter.

In the position of the various switches and contacts which is shown in Fig. 1 the receiver is suited to the reception of a signal to which the receiver has been tuned by pressing-in the key T_2 . The contact I of the switch-arm is located on that contact of the contact track 1 which is connected to the fixed contact of the switch actuated by the key T_2 with the result that the alternating voltage set up across the winding 5 is supplied to the coupling magnet M.

The coupling magnet M has to perform two functions. Firstly, upon excitation of the magnet M the contact m is opened and secondly the excitation of the magnet M results in that the shaft 10 becomes coupled with the shaft 11, the latter being effected with the aid of a differential coupling 12 which is shown in detail in Fig. 2.

In Fig. 2 the driving shaft is denoted by 11. This shaft is surrounded by a casing 13 in which run a plurality of balls 14, which are in contact both with the shaft 11 and with the casing 13. The balls 14 run in a cage 15 which has secured to it the shaft denoted in Fig. 1 by 10. When the shaft 11 rotates and the casing 13 is held fast, the balls roll along the inner surface of the casing 13 and put the cage 15 into motion. The cage 15 and the shaft connected thereto turn in this case at a smaller speed of rotation than the shaft 11 and in the same direction.

If, on the contrary, the shaft 11 is turned and the casing 13 is not held fast, the balls 14 cannot roll on the inner surface of the casing. In this case the casing 13 follows the rotary movement in opposite direction but the cage 15 remains at rest.

The casing 13 may be held fast with the aid of the coupling magnet M. If the coupling magnet is not excited, the shaft secured to the cage 15 is not actuated. As soon, however, as the magnet is excited the casing 13 stops and the shaft connected to the cage 15 starts turning. In this way one obtains an extremely simple coupling which can be electrically switched on and off at will.

The coupling magnet M is so dimensioned that for retaining the casing 13 a higher exciting voltage is required than for the opening of the contact m . When the magnet M is excited by the alternating voltage set up across the secondary winding 4 the contact m is opened and, in addition, a coupling between the shafts 10 and 11 is brought about. If, however, the excitation of the magnet M is brought about by the lower voltage set up across the secondary winding 5, the contact m is broken, it is true, but a coupling between the shafts 10 and 11 is not brought about.

When the various contacts occupy the positions shown in the figure, in which event the receiver is tuned to a signal by means of the key T_2 the contact m is consequently opened but the shaft 10 is not coupled with the shaft 11.

If it is desired to tune the receiver to another station another key, for example the key T_1 , is pressed-in. The key T_2 , which was pressed-in, automatically snaps upwards and thus interrupts the circuit through which the magnet M is excited with the result that the contact m is closed and the motor M_t starts running. The shaft 11 is actuated and through the intermedi-

ary of gear wheels 16 and 17 it actuates a shaft 18 on which a disc 19 is rigidly mounted. As soon as the shaft 18 is actuated the contact k is closed in a manner which will be described later on. The disc 19 has secured to it a carrier 20 which engages an extension 21 of a disc 22 which is free to rotate on the shaft 18. The disc 22 has secured to it a carrier 23 which actuates, with the aid of a pin 24, a disc 25 mounted on a shaft 26. The latter shaft actuates a tuning condenser 27 which is consequently set in motion and this, owing to the fact that the diameter of the gear wheel 16 is considerably larger than that of the gear wheel 17, at a high speed.

The driving at high speed of the tuning means proceeds unaltered until the contact I of the switch arm, which moves along the contact track in the direction indicated by the arrow 28, reaches the contact of said contact track which is connected via the pressed-in key T_1 to the conductor 2. At this instant the voltage set up across the secondary winding 4 is supplied to the coupling magnet M with the result that the shaft 10 becomes coupled with the shaft 11 and the contact m is opened. The opening of the contact m does not, however, result in the motor M_t being switched out of circuit since meanwhile the contact k has been closed.

Through the intermediary of bevel gear wheels 29 and 30 the shaft 10 actuates a shaft 31 which is coupled by means of a slip coupling 32 to a shaft 33. The shaft 33 has mounted on it a lever 34 which, owing to the rotation of the shaft 33, is shifted to the right, against the action of a spring 35 and by which at the same time a bush 36 keyed to the shaft 26 is likewise moved to the right. The shaft 26 is thus displaced to such an extent that the gear wheel 37 comes into engagement with a gear wheel 38, the pin 24 getting clear of the carrier 23. The gear wheel 38 is mounted on a shaft 39 which has also mounted on it a second gear wheel 40 which meshes with a gear wheel 41 mounted on the shaft 10. Through the intermediary of the gear wheels 40 and 41 the shaft 10 consequently actuates the shaft 39 which actuates in its turn, by means of the gear wheels 37 and 38, the shaft 26 so that now, owing to the fact that the diameter of the gear wheel 37 is large with respect to the diameter of the gear wheel 38, the tuning means are actuated at a considerably reduced speed. At the same time when the lever 34 moves to the right the contact h is closed.

As is shown in detail in Figs. 3 and 3a, a spring 42 is laid around the shaft 18 between the discs 19 and 22, opposite ends of the spring being anchored in the respective discs. The action of the spring 42 is normally to separate the extension 21 from the carrier 20 as shown in Fig. 3a. However, due to the coupling between discs 22 and 25 by way of the carrier 23 and pin 24 and the driving action of disc 19 which supports the carrier 20, the latter is forced to exert a driving force or pressure against extension 21, as shown in Fig. 3, in opposition to the spring action of 42. As soon as the contact between the carrier 23 and the pin 24 is broken owing to the action of the lever 34, the disc 22 being loose on the shaft is turned back, due to the pressure exerted by the spring 42, over an angle of almost 360° with respect to the disc 19 with the result that the extension 21 assumes the position shown in Fig. 3a. Moreover, owing to the fact that the disc 22 which carries the extension 21 turns back, the contact k is opened in

a manner which will be described more fully. The opening of the contact *k* does not, however, result in the motor *Mt* being switched out of circuit since meanwhile the contact *h* has been closed by the action of the lever *34*.

The actuation at slight speed of the tuning means continues until the contact *II* of the switch arm has reached that contact of the contact track *I* which is connected via the key *T₁* to the conductor *2*. At this instant the coupling magnet *M* has applied to it, instead of the alternating voltage of the secondary winding *4*, the appreciably smaller alternating voltage of the winding *5* with the result that the coupling between the shafts *10* and *11* is broken whereas the contact *m* remains open. The shaft *10* stops so that the shaft *31* is no longer actuated. Now the lever *34* is moved to the left by the spring *35* with the result that the contact *h* is opened. Now all the three contacts *m*, *h* and *k* are opened so that the motor is switched off. Due to the fact that the actuation of the shaft *10* is stopped the condenser *27* has stopped at once.

After being switched off the motor of course continues running for some time due to its inertia but it can no longer actuate the tuning means because it is effectively disconnected from the shaft. It is true that during the movement of the lever *34* to the left the shaft *26* has also been moved to the left to such an extent that the pin *24* comes again into engagement with the carrier *23* but this engagement does not bring about at once the actuation of the shaft *26* since, due to the action of the spring *42*, the carrier *20* is on the wrong side of the extension *21* (as is shown in Fig. 3a) and consequently cannot transfer any force to said extension. To that end it is necessary first to apply a force in opposition to the pressure of the spring *42* and to bring the carrier *20* to the other side of the extension *21* (as is shown in Fig. 3), which requires a complete revolution of the shaft *18*. Before this revolution has been performed, the motor has stopped.

As to the construction of the switches *h* and *k* the following may be observed. The switch *h* may consist of two resilient contact tongues which are pressed against one another by the lever *34* when the latter moves to the right. In its simplest construction, as shown in Fig. 3, the switch *k* consists of two contact tongues which are secured to the carrier *20* and the extension *21* respectively and consequently only make contact with one another when (with the arrangement shown in Fig. 3) the carrier *20* is located on the left-hand side of the extension *21* or in other words when the shafts *18* and *26* are coupled with one another. During the slow actuation of the tuning means the switch *k* is consequently opened. This switch is also open during the period of time in which the receiver is tuned to a station and this owing to the fact that the motor stops before the spring *42* has been completely stretched, i. e. before the carrier *20* is pressed again against the left-hand side of the extension *21*. When, in order to tune the receiver to another station, one of the keys of the station selector is pressed-in, the shaft *26* is consequently not actuated at once but first the spring *42* is further stretched until the carrier *20* engages the left-hand side of the extension *21*, at which moment at the same time the switch *k* is closed and the shaft *26* is set in motion.

Figs. 4 and 5 represent another embodiment of the invention. These figures represent a portion

of a receiving apparatus with completely automatic tuning, wherein use is made in known manner of a plurality of profiled discs *S₁*, *S₂*, *S₃*, *S₄* (Fig. 5) which are mounted on a shaft *44* by which the tuning members (diagrammatically represented in Fig. 5 by a tuning condenser *21*) are actuated. Such a disc is provided for each station to which the receiver can be tuned by means of the station selector.

10 As in the embodiment according to Fig. 1 the station selector consists of a key-board on which a key is provided for each of the stations to which the receiver can be automatically tuned. The key-board is constructed in such manner that always only a single key can be pressed-in. When another key is pressed-in, the key which has previously been pressed-in automatically snaps up.

In Fig. 4 one of the keys is denoted by *T* and 20 the corresponding disc which is mounted on a shaft *44* is designated by *S*. The circumference of the disc *S* consists of a portion *45* of large diameter and of a portion *46* of smaller diameter, which portions are connected to one another by a sloping portion *47*. On the circumference of the disc *S* runs a feeler *48* which is permanently pressed against the circumference by means of an expansion spring *48'*, said feeler having secured to it a lever *49* by means of which a disc 30 *50* is turned on its shaft *51* when the feeler *48* moves up and down. The disc *50* is made of insulating material, with the exception of portions *52*, *53* and *54* of the circumference which consist of conductive material. Conductors *56*, *57* and *58* are connected to these points of contact *52*, *53* and *54*. In contact with the circumference of the disc *50* there is provided a brush *55* which, upon rotation of the disc, comes in 35 turn into contact with the points of contact *52*, *53* or *54*. The brush *55* is connected via the tuning key *T* to a conductor *59*.

For each of the stations to which the receiver 40 can be automatically tuned there are provided corresponding conductors *56*, *57*, *58* and *59*. A second set of such conductors is denoted in the figure by *60*. The corresponding conductors *56*—*59* of each of the stations are multiple or shunt-connected to four common conductors *61*, *62*, *63* and *64*.

50 Via a switch *65* whose operation will herein-after be described more fully, the conductor *61* is connected to one of the terminals *66* of the alternating current mains. The conductors *62* and *63* are connected, each through one of the 55 exciting windings *67* and *68* of the motor *Mt*, to the other terminal *69* of the mains. The conductor *64* is connected to the terminal *69* via a brake magnet *70* which serves to stop the tuning members after the desired tuning has been attained.

The two exciting windings *67* and *68* of the 60 motor *Mt* are wound in opposite senses in such manner that upon connecting the mains to the winding *67* the motor rotates, for example in a clockwise direction whereas when the mains are connected to the winding *68* an opposite direction of rotation of the motor is obtained. Those ends of the windings *67* and *68* which are connected to the conductors *62* and *63* are connected to one another through the intermediary of a condenser *71*. It is thus obtained that when the mains are connected to one of the windings an out-of-phase current is supplied to the other winding so that a rotating field is set up which 65 puts the rotor in motion.

The motor M_t further possesses the property known in itself that when the stator is not excited the rotor is located outside the stator and, upon excitation, is drawn into the latter. According to the invention, this property is utilised for reducing the speed of actuation of the tuning members to an appreciable extent just before the desired tuning is obtained. The manner in which this occurs will be explained more fully with reference to Fig. 5.

In Fig. 5 the stator of the motor M_t is denoted by 72 and the rotor by 73. A flywheel 75 is mounted on the shaft 74 of the rotor. The figure illustrates the case wherein the stator is not excited, in which event the rotor is pressed to the right out of the stator by a spring 76 which acts in the direction indicated by the arrow. A gear wheel 77 mounted on the shaft 74 meshes in this case with a gear wheel 78 whose diameter is large with respect to the diameter of the gear wheel 77 so that the shaft 79 on which the gear wheel 78 is mounted is driven at a low speed as long as the shaft 74 is moving.

If now the stator 72 is excited, the rotor 73 is drawn into the stator against the action of the spring with the result that the shaft 74 moves to the left to such an extent that a gear wheel 80 of large diameter, which is mounted on the shaft 74, engages a gear wheel 81 of small diameter which is mounted on the shaft 79. In this case the shaft 79 is actuated at a high speed.

By means of a friction coupling 82 the shaft 79 is coupled with a shaft 44 on which discs S_1 to S_4 and tuning members 27 are mounted. The shaft 44 has mounted on it a brake disc 83 with the aid of which, upon attainment of correct tuning, the tuning members are stopped at once owing to the excitation of a brake magnet 70.

According to the invention, the above-described construction is utilised in such manner that the excitation of the stator 72 is switched off just before the desired tuning position is attained. Owing to the mounting of the flywheel 75 on the shaft of the rotor the latter does not stop at once when the stator is switched off but continues to turn for a considerable time at an almost unreduced speed. Due to the suppression of the excitation of the stator the rotor 73 flies, however, to the right, thus bringing the gear wheels 77 and 78, instead of the gear wheels 80 and 81, into engagement with one another with the result that the speed at which the shaft 79 is driven is considerably reduced. As soon as correct tuning is attained the brake magnet 70 is excited with the result that the tuning members are braked. Then the motor continues to run for some further time but owing to the presence of the friction coupling 82 it cannot draw the tuning members through the brake.

The manner in which the switching-off of the stator and the excitation of the brake magnet are effected will hereinafter be explained more fully with reference to Fig. 4.

In Fig. 4 the disc S is shown in the position occupied by this disc at the moment when the tuning members come at rest. Such is the case when the feeler 48 is just in the middle of the sloping portion 47 owing to the fact that at this moment the disc 50 occupies a position such that the brush 55 makes contact with the point of contact 54 so that via 66, 65, 61, 59, T, 55, 54, 57, 64, 70 and 69 a circuit is closed and consequently the brake magnet 70 is excited with the result that the tuning members and the discs S_1 — S_4 immedi-

ately stop. The point of contact 54 is made as narrow as possible in order to ensure very correct tuning. The minimum width of the point of contact 54 is determined by the time which elapses between the moment when the above-mentioned circuit is closed and the moment when the tuning members come at rest, and by the speed of revolution of the disc 50. The lower the speed of revolution of the tuning members upon attainment of correct tuning, the narrower may be the point of contact 54 be taken. The accuracy of tuning consequently increases as the speed of the tuning members upon attainment of correct tuning is decreased.

If it is desired to tune the receiver to another station, the key T corresponding to this station is pressed-in owing to which the key which has previously been pressed-in automatically snaps upwards and interrupts the circuit of the brake magnet 70.

At the moment when the key is pressed-in the disc S corresponding to the pressed-in key occupies an arbitrary position. The feeler 48 may consequently be on the portion of large diameter 45 or on the portion of small diameter 46 or on the sloping portion 47 of the circumference of the disc S . If the feeler 48 is on the portion 45 of the circumference of the disc S , the disc 50 will have turned clockwise to such an extent that the brush 55 makes contact with the point of contact 53. In this case, upon pressing-in the key T, a circuit 66, 65, 61, 59, T, 55, 53, 58, 62, 67, 69 is closed so that the exciting winding 67 of the motor M_t is connected to the mains. The motor starts running and this in clockwise direction. Owing to the excitation of the winding 67 the rotor 73 (Fig. 5) is drawn into the stator with the result that the gear wheels 80 and 81 are caused to mesh with one another. The tuning members consequently turn at a high speed, and this in counter-clockwise direction so that the feeler 48 moves with respect to the disc S towards the sloping portion 47.

If, on the contrary, upon pushing-in the key T, the feeler 48 is in contact with the portion of small diameter 46 of the circumference of the disc S the disc 50 occupies a position such that the brush 55 makes contact with the point of contact 52. Upon pressing-in the key T the winding 68 of the motor M_t is connected in this case to the mains with the result that the motor rotates in opposite direction. Again in this case the feeler 48 moves with respect to the disc S towards the sloping portion 47.

In both cases the actuation at high speed of the tuning member continues until the feeler 48 reaches the sloping portion 47 of the circumference of the disc S . At this instant the disc 50 starts rotating and after a short time it interrupts the motor circuit owing to the fact that the brush 55 leaves the point of contact 52 or 53 and reaches an insulated portion of the circumference of the disc 50, which results in that the motor is switched off and the speed at which the tuning members are actuated is considerably reduced in the above-described manner. The tuning members continue to rotate at a low speed, the feeler passing meanwhile over the sloping portion 47 of the circumference of the disc S . As soon as the feeler has reached the middle of this sloping portion the disc 50 has taken a position such that the brush 55 makes contact with the point of contact 54 with the result that the brake magnet 70 is excited and the tuning members are braked.

A complication occurs if two stations having a slight difference in frequency are selected the one after the other by means of the station selector. For in this case it may occur that, upon pressing-in the key T, the feeler 48 is already on the sloping portion 47 of the circumference of the disc S so that upon pressing-in the key the motor circuit would not be closed. In order to prevent this there has been provided a switch 65 with the aid of which one of the motor windings can be directly connected to the mains.

After the switch 65 has been shifted different cases may occur. At this instant one of the points of contact 52 or 53 of the disc 50 will in general make contact with the brush 55 so that either 15 the motor continues to rotate in the same direction or reverses its direction of rotation and then causes the tuning members in the above-described manner to occupy the desired position.

It may also occur that after the switch 65 has been shifted the feeler 48 is on the sloping portion 47 of the circumference of the disc S so that by shifting the switch 65 the motor circuit is interrupted. Owing to the presence of the flywheel the motor still continues to run for some time, thus actuating the tuning members at a low speed. If upon shifting the switch 65 the desired position of the tuning members had not yet been attained, this actuation continues until the brush 55 makes contact with the point of contact 54 of the disc 50, at which instant the tuning members are braked. If, on the contrary, when the switch 65 had been shifted, the tuning members had already passed the desired position the motor continues to run until the brush 55 comes into contact with any of the points of contact 52 and 53 and then reverses its sense of rotation and brings the tuning members into the desired position from the other direction.

The transmission shown in Fig. 5 wherein the motion of the motor shaft is transmitted by means of gear wheels to the shaft of the tuning condensers, has the drawback that at the moment when the gear wheels come into engagement with one another they have different peripheral speeds, which may give rise to an annoying cracking noise upon changing-over and to a rapid tear and wear of the gear wheels. This drawback may be removed by utilising friction couplings instead of gear wheels.

What I claim:

1. In a control shaft positioning means including a plurality of selectively operable devices each acting upon selective operation to position the shaft to any one of a plurality of different positions, a reversible electric motor, variable speed transmission means for connecting the motor to the control shaft, a plurality of operable switching means associated with said selectively operable devices each thereof having positions for operating the motor in a forward and reverse direction, and a neutral position for stopping the motor, means connected for operation with said control shaft for operating said switching means, means acting in response to operating potential applied to the motor for adjusting the variable speed transmission means so as to provide a high speed driving connection between the motor and the control shaft, and means for adjusting the variable speed transmission means to provide a low speed driving connection between the motor and the control shaft upon removal of the motor operating potential.

2. In a shaft positioning system, an adjustable shaft, a reversible motor for driving said shaft, 75

variable speed transmission means connected between the motor and the adjustable shaft, a source of energizing current for the motor, a plurality of motor circuits adapted to be connected between the motor and the source of current, one of said circuits acting upon connection thereof to effect the operation of the motor in one direction, the other of said circuits acting upon connection thereof to effect the operation of the motor in the opposite direction, an operable main switch, a multi-position selectively operable switching means arranged so that with the main switch closed the motor is connected to the source through one of said pair of motor circuits in one position of the multi-position switching means, the motor is connected to the source through the other of said pair of motor circuits in another position of the switching means, and the motor is de-energized in an intermediate position of the switching means, means connected to said adjustable shaft for operating said selectively operable switching means, said motor being arranged so as to control the variable speed transmission means in such a way that a low transmission ratio of coupling between the motor and the adjustable shaft is provided when the motor is in a de-energized condition whereas a high transmission ratio is provided when the motor is energized, said motor being arranged so that in the operation thereof sufficient momentum is provided to maintain the motor in operation for an appreciable length of time after the motor is de-energized.

3. The arrangement described in claim 2 in combination with operable means for braking the motor, said means becoming operative to stop the motor when said main switch is closed and the selectively operable switching means assumes said intermediate position.

4. The arrangement described in claim 2 characterized by that the motor is of the type wherein the armature is shifted upon an energizing potential being applied to the motor and by that means are provided for operating the variable speed transmission means in accordance with the position of the motor armature.

5. In a control system, a control shaft, an electric motor for driving said shaft, multi-step transmission means coupling the motor to the control shaft, said motor having a movable element acting in response to operating potential applied to the motor for adjusting the change speed means to provide a driving connection between the motor and the control shaft through one of the steps of said transmission means, and means acting upon removal of the motor operating potential for adjusting the change speed means to provide a driving connection between the motor and the control shaft through another one of said transmission steps.

6. In the arrangement described in the next preceding claim, a plurality of selectively operable means for controlling the operation of the motor, each of said selectively operable means representing a desired position of said control shaft, means acting upon operation of one of said selectively operable means for applying an operating potential to said motor and thereby cause the motor to operate the control shaft toward the position represented by the operated selectively operable means and means for removing the motor operating potential just prior to the control shaft reaching the desired position.

7. In a control shaft positioning system of the type which includes an electric motor the opera-

tion of which is controlled by means of a plurality of selectively operable devices each acting upon selective operation thereof to effect through operation of the motor the adjustment of the control shaft to any one of a plurality of positions by applying an operating potential to the motor to thereby start the motor running and removing the operating potential when the control shaft has been brought to a position which is near that represented by the operated selectively operable device, said positioning system being arranged to have sufficient momentum once it is set in motion to drive the control shaft an appreciable distance beyond the point of cut-off of the motor operating potential, variable speed transmission means coupling the motor to the control shaft, means acting in response to operating potential applied to the motor for adjusting the variable speed transmission means so as to provide a high speed driving connection between the motor and the control shaft, means for adjusting the variable speed transmission means to provide a low speed driving connection between the motor and the control shaft upon cut off of the motor operating potential, and means for braking the motor when the control shaft reaches the desired position.

8. In a control system, a control shaft, a source of current, a reversible motor for driving said shaft, variable speed transmission means coupling the motor to the control shaft, means acting in response to operating potential applied to the motor for adjusting the variable speed transmission means so as to provide a high speed driving connection between the motor and the con-

35 trol shaft, means for adjusting the variable speed transmission means to provide a low speed driving connection between the motor and the control shaft upon cut off of the motor operating potential, means for braking the motor when the control shaft reaches the desired position, a plurality of reversing switches for the motor, each of said reversing switches having positions for operating the motor in a forward and a reverse direction and a range of neutral positions of appreciable extent intermediate said forward and reverse positions for stopping the motor, a plurality of selectively operable switches one for each of said reversing switches, each of said selectively operable switches being in circuit with its reversing switch and the motor and acting upon operation to connect the motor to the source when said reversing switch is in an operating position, operating means for the reversing switches connected with the control shaft and arranged so that operation of one of said selectively operable devices effects the movement of its associated reversing switch to a position which is within said neutral range of positions in response to movement of said control shaft, and an auxiliary switching means for providing a direct connection between said motor and said source of current to thereby assure energization of the motor in the event that the reversing switch of an operated selectively operable device is within said neutral range of positions and for breaking said direct connection between the motor and the source of current after said motor has operated for a predetermined interval of time.
